UNITED STATES PATENT OFFICE

2,090,516

VOLTAGE REGULATING SYSTEM

Clarence J. Kettler and Levin W. Foster, Pittsfield, Mass., assignors to General Electric Company, a corporation of New York

Application July 9, 1936, Serial No. 89,746

10 Claims. (Cl. 171—119)

Our invention relates to voltage regulating systems and more particularly to electric valve circuits for controlling the relative voltages of associated electric circuits.

Heretofore there have been devised numerous arrangements for controlling the relative voltages of associated electric circuits by means of interposing electric valve means. For example, in arrangements including tap changing transformers, electric valve means have been employed to control the interconnection of the associated circuits through the terminals of the transformer windings. In certain of the prior art arrangements, the electric valve means have been controlled in accordance with the voltages of the associated circuits to effect selective energization of the electric valve means to control the relative voltages of the circuits. There has been a decided need for improved voltage regulating systems of the type employing electric valve means which will effect the desired selective energization of the various associated electric valve means in accordance with an electrical condition of the associated circuits and which will accomplish a smooth and precise transfer of load current among the electric valve means.

It is an object of our invention to provide a new and improved electric valve voltage regulating system for use in connection with a multi-terminal transformer, whereby the transfer of load current among the various electric valve means is accomplished in a precise and reliable manner in accordance with an electrical condition of one of the associated circuits.

It is another object of our invention to provide an electric valve voltage regulating system to be used in connection with multi-terminal transformers whereby the transfer of the load current among the various electric valves is effected in accordance with the voltage of one of the associated circuits and in which the excitation circuits for the various electric valve means are arranged so that the load transfer is effected when the instantaneous value of the load current is substantially zero.

In accordance with the illustrated embodiments of our invention, we provide new and improved electric valve voltage regulating systems of the type adapted to be used in connection with multi-terminal transformer windings in which the voltage control is effected by the selective energization of the various electric valve means to control the relative voltages of the associated circuits. Electric valve means including pairs of electric valves, reversely connected in parallel,

are connected to the various terminals of the associated transformer windings and are employed to connect selectively the transformer terminals to one of the associated circuits to accomplish the desired voltage control. A plurality of excitation circuits, each associated with a different pair of electric valves, serve to control the energization of the electric valves to render them conductive to effect the transfer of current in both directions through the transformer winding. Current responsive means, such as reactors or resistors, are connected in series relation with each pair of electric valves to effect transfer of the load current among the various electric valve means when the instantaneous value of the load current is substantially zero. The excitation circuits are controlled in accordance with an electrical condition, such as the voltage of one of the associated circuits. For example, a contact making voltmeter may be employed to effect the selective energization and deenergization of electric valve means in order to accomplish the desired transfer in load current. The current responsive means control the excitation circuits so that only the electric valve means associated with one of the transformer terminals are rendered conductive at any one time and are arranged so that even though the contact making voltmeter dictates a load transfer, this transfer will not be effected until the instantaneous value of the load current is substantially zero. In a modified embodiment of our invention, phase shifting means are interposed between the current responsive means and the excitation circuits to introduce in the excitation circuits potentials which are substantially 180 electrical degrees out of phase with the potentials impressed on the anodes of the electric valves to which the transfer is to be made. In this manner the excitation circuits are controlled to assure that the transfer will be made at exactly the time when the instantaneous value of the load current is zero.

For a better understanding of our invention, reference may be had to the following description taken in connection with the accompanying drawings and its scope will be pointed out in the appended claims.

Fig. 1 of the accompanying drawings diagrammatically represents an embodiment of our invention in which the transfer of the load current between various terminals of a multi-terminal transformer winding is accomplished in accordance with an electrical condition of an associated circuit. modified arrangements in which electric valve means, of the type employing immersion-ignitor control members, control the relative voltages of the associated circuits in accordance with an electrical condition of one of the circuits.

Referring to Fig. 1 of the accompanying drawings, our invention is diagrammatically shown as applied to a voltage regulating system. An alternating current supply circuit 1 is employed to 10 energize an alternating current load circuit 2 through a transformer 3 including a primary winding 4 having voltage controlling terminals 5 and 6. Electric valve means including electric valves 7 and 8, which are reversely connected in 15 parallel, are associated with terminal 5, and electric valve means including electric valves 9 and 10, also reversely connected in parallel, are associated with terminal 6 of transformer winding 4. The electric valves 7, 8, 9 and 10 are preferably 20 of the type employing ionizable mediums, such as gases or vapors, and each includes an anode 11, a cathode 12 and a control member 13. Short-circuiting switches 14 and 15 are connected to shunt electric valves 7 and 8, and 9 and 10, respectively, when tap changing functions are not being performed by these electric valves. Excitation circuits 16 and 17 are employed to control the energization of electric valves 7 and 8, and 9 and 10, respectively. Considering excitation 25 circuits 16 in particular, a transformer 18 having primary windings 19 and 20 and secondary windings 21 serves to render the electric valves 7 and 8 alternately conducting so that current may be transferred in both directions through the left-hand portion of primary winding 4 of transformer 3. Any suitable source of alternating potential 30 22 of the same frequency as that of alternating current supply circuit 1 serves to energize primary windings 19 of transformers 18 in excitation 35 circuits 16 and 17. Current limiting resistances 23 are connected in series with the control members 13 of electric valves 7, 8, 9 and 10. In order to control selectively the energization of excitation circuits 16 and 17 in accordance with 40 an electrical condition, such as the voltage of the load circuit 2, we employ any suitable arrangement such as a voltage responsive means 24 including an actuating winding 25, a spring biased plunger 26, a movable contact member 27 and 45 stationary contacts 28 and 29. The stationary contact 28 is employed to effect energization of excitation circuit 16 and the stationary contact 29 is arranged to effect energization of excitation circuit 17. A transformer 30 connects the alternating current load circuit 2 to the voltage responsive means 24. While we have shown the voltage responsive means 24 as being energized from the alternating current load circuit 2, it should be understood that the voltage responsive 50 means may be connected to the alternating current supply circuit 1 to effect control of the system in accordance with the voltage of the supply circuit 1.

To provide a means for effecting transfer of 60 the load current between terminals 5 and 6 when the instantaneous value of the load current is substantially zero, we employ current responsive means such as resistances 31 and 32 which are connected in series relation with electric valves 7 and 8, and 9 and 10, respectively. A voltage which varies in accordance with the voltage appearing across the resistance 31 is introduced in the excitation circuit 17 by means of primary winding 20 of transformer 18 and is correlated in 65 phase so that the excitation circuit 17 maintains

electric valves 9 and 10 non-conducting so long as the electric valves 7 and 8 are conducting current, even though the voltage responsive means 24 dictates a transfer of load current from electric valves 7 and 8 to electric valves 9 and 10. In like manner, a voltage which varies in accordance with the voltage appearing across resistance 32 is introduced in excitation circuit 16 through primary winding 20 of transformer 18 to maintain electric valves 7 and 8 non-conducting so long as electric valves 9 and 10 are conducting current and this controlling action is maintained even though voltage responsive means 24 dictates a transfer from electric valves 9 and 10 to electric valves 7 and 8.

While in Fig. 1 of the accompanying drawings we have diagrammatically shown our invention as applied to a transformer tap changing arrangement in which the transformer is provided with only two terminals, it should be understood that our invention may be applied to electric valve transformer tap changing circuits in which any number of terminals are used.

The general principles of operation of the embodiment of our invention diagrammatically shown in Fig. 1 may be best explained by considering the voltage regulating system when the primary winding 4 of transformer 3 is being energized from the alternating current circuit 1 through electric valves 9 and 10. Let it be assumed that the voltage responsive means 24 is adjusted to maintain a predetermined range of voltages of the alternating current load circuit 2 and let it be further assumed that the load current in the circuit 2 has increased so that the voltage of the circuit 2 has decreased below the predetermined minimum value. Under these conditions, the spring biased plunger 26 of voltage responsive means 24 will have been moved to the position shown in Fig. 1 of the drawings to dictate an increase in the voltage of the load circuit 2. By virtue of the fact that the movable contact member 27 is placed in engagement with stationary contact 28, the primary winding 19 of transformer 18 in excitation circuit 16 will be energized, tending to render electric valves 7 and 8 conductive. However, excitation circuit 16 will not render electric valves 7 and 8 conductive until the value of current conducted by electric valves 9 and 10 is substantially zero by virtue of the fact that the voltage introduced in excitation circuit 16 by means of primary winding 20 of transformer 18 tends to render ineffective the potential introduced in this circuit by primary winding 19. When the current conducted by electric valves 9 and 10 passes through zero, excitation circuit 16 will render electric valves 7 and 8 conductive so that the voltage of supply circuit 1 is impressed between the left-hand terminal of primary winding 4 and terminal 5 of transformer 3 to effect the desired increase in the voltage of alternating current load circuit 2. On the other hand, if the voltage of the alternating current load circuit 2 increases to a value greater than the predetermined maximum value for which the voltage responsive means 24 is adjusted, the spring biased plunger 26 will be actuated so that the movable contact member 27 engages the stationary contact 29 to impress in primary winding 19 of transformer 18 in excitation circuit 17 a potential tending to render electric valves 9 and 10 conductive. The voltage introduced in excitation circuit 17 by means of the resistance 31 and the primary winding 20 will

prevent electric valves 9 and 10 from conducting current until the instantaneous value of the load current is substantially zero. When the load current passes through the zero value, this biasing potential will be removed and electric valves 9 and 10 will be rendered conductive effecting thereby the desired decrease in the voltage of the alternating current load circuit 2.

In Fig. 2 of the accompanying drawings our invention is diagrammatically illustrated as applied to an electric valve voltage regulating system in which electric valves of a type employing immersion-ignitor control members are used. An alternating current supply circuit 33 energizes a transformer 34 having a secondary winding 35 and an extension 35' to the secondary winding which is inductively associated with the secondary winding 35. An alternating current load circuit 36 is arranged to be energized from the lower terminal of the secondary winding 35 and the upper terminal of extension winding 35'. The extension winding 35' of the secondary winding is provided with electric terminals or taps 37, 38, 39, 40 and 41 and associated switching means 42 and 43. Electric valves 44, 45, 46 and 47, of the type employing immersion-ignitor control members and each including an anode 48, a mercury pool cathode 49 and an immersion-ignitor control member 50, are electrically interposed between the secondary winding 35 and the extension 35' of secondary winding 35 to control selectively the voltage of the alternating current load circuit 36. Electric valves 44 and 45, and 46 and 47, respectively are reversely connected in parallel so that alternating current may be conducted through the secondary winding 35 and extension winding 35'. Switches 51 and 52 are connected to short circuit the electric valves 44 and 45, and 46 and 47, respectively, to eliminate the arc-drop incident to discharge through these electric valves when the electric valve system is not being employed in a tap changing operation.

In order to control the conductivity of electric valves 44, 45 and 46, 47, excitation circuits 53 and 54 respectively serve to render the electric valves of each group alternately conductive. Each of the excitation circuits 53 and 54 includes a transformer 55 having a primary winding 56 and secondary windings 57. Referring in particular to excitation circuit 53, the lower secondary winding 57 is associated with the immersion-ignitor control member 50 of electric valve 44 and supplies pulses of unidirectional current to this control member through a unidirectional conducting device 58. Similarly, the upper secondary winding 57 of transformer 55 is associated with the control member 50 of electric valve 45 and periodically renders the valve 45 conductive by supplying a pulse of unidirectional current through the unidirectional conducting device 59. In similar manner, the secondary windings 57 of transformer 55 in excitation circuit 54 control the conductivity of electric valves 46 and 47. A suitable source of alternating potential 60, preferably of the same frequency as that of the alternating current supply circuit 33, impresses alternating potentials on the primary windings 63 and 64 of transformers 61 and 62, respectively. A voltage responsive means 65 selectively energizes the primary windings 63 and 64 of transformers 61 and 62 in accordance with the voltage of the alternating current load circuit 36 to control the electric valve tap changing system to energize the various groups of electric valves associated with

the different terminals of the extension winding 35'.

To provide a voltage which varies in accordance with the current conducted by electric valves 44-47, we employ current responsive means such as reactors 66 and 67 which are connected in series relation with electric valves 44 and 45, and 46 and 47, respectively, and which are interposed between these pairs of electric valves and the extension winding 35'. Phase shifting circuits 68 and 69, having capacitances 10 and 11 and variable resistances 12 and 13, respectively, are interposed between the reactors 66 and 67 and excitation circuits 53 and 54 to modify the phase of the potential introduced into the excitation circuits 53 and 54. The reactor 66 and the phase shifting circuit 68 are arranged to introduce in the excitation circuit 54, through a transformer 74 having a primary winding 75 and a secondary winding 76, a potential which is substantially 180 electrical degrees out of phase with the potential impressed on the control members 50 of electric valves 46 and 47. By virtue of the fact that this potential exists only so long as current is conducted through the reactor 66, this 180 electrical degree displaced potential will be present in the excitation circuit 54 only during the interval when current flows in electric valves 44 and 45. An impedance 77 having a negative impedance-current characteristic, such as the material disclosed and claimed in U. S. Patent 1,822,742 granted September 8, 1931 on an application of K. B. McEachron and assigned to the assignee of the present application, is connected across the secondary winding 76 of transformer 74 to suppress high voltage transients which may be introduced into the excitation circuit 54 by virtue of current disturbances in the alternating current load circuit 36. The reactor 67 and the associated phase shifting circuit 69 are associated with excitation circuit 53 in a similar manner through a transformer 78.

The operation of the embodiment of our invention diagrammatically shown in Fig. 2 may be best explained by assuming that electric valves 46 and 47 are conductive to impress on the alternating current load circuit 36 a potential through switch 43 and tap 38 of extension winding 35'. If it be assumed that the potential of the alternating current circuit 36 has decreased to a value less than the predetermined minimum value for which the voltage responsive device 65 has been adjusted, the device 65 will have been moved to the position shown in the figure to remove the potential impressed on primary winding 64 of transformer 62 and to impress a potential on primary winding 63 of transformer 61. This potential tends to energize excitation circuit 53 and thereby effect energization of control members 50 of electric valves 44 and 45. However, the potential incident to the flow of current through reactor 67 is introduced in excitation circuit 53 through the phase shifting circuit 69 and transformer 78 to render ineffective the potential introduced in the excitation circuit by the transformer 61. By the proper adjustment of the resistance 73 of phase shifting circuit 69, the potential introduced into the excitation circuit 53 may be made to be in exact phase opposition to the potential introduced into the circuit by transformer 61. If the circuit 60 is connected to be energized from the alternating current supply circuit 33, or from a circuit having a potential exactly in phase with the alternating current circuit 33, electric valves 75

44 and 45 will be maintained non-conductive until the instantaneous value of the current flowing through the reactor 67 is substantially zero. At that instant the potential introduced in excitation circuit 53 by transformer 61 will become effective to alternately energize control members 50 of electric valves 44 and 45 to connect the load circuit 36 to terminal 37 of extension winding 35, thereby effecting an increase in the potential of 10 the alternating current circuit 36.

By the proper adjustment of the constants of the phase shifting circuits 68 and 69, the transformer tap changing system may be arranged to operate under any particular power factor conditions. In order to operate most satisfactorily, these circuits should be adjusted for the most lagging power factor condition.

In a similar manner, when the voltage of the alternating current circuit 36 increases above a 20 predetermined value, the electric valve voltage controlling system will be effective to transfer the load current from the electric valves 44 and 45 to electric valves 46 and 47 at the time when the instantaneous value of the load current is substantially zero.

Fig. 3 of the accompanying drawings diagrammatically represents a modified embodiment of our invention which is quite similar in construction and arrangement to that shown in Fig. 2, 30 differing only in regard to the type of excitation circuit employed, and corresponding elements have been assigned like reference numerals. In Fig. 3 excitation circuits 79 and 80 of the impulse type are associated with electric valves 44, 45 and 46, 47, respectively. The excitation circuits 79 and 80 are similar in construction and arrangement. Referring to excitation circuit 79 in particular, control electric valves 81 and 82, preferably of the type employing ionizable 35 diodes, are associated with electric valves 44 and 45, respectively, and serve to supply impulses of current to control members 50 of these valves. To provide means for supplying impulses of current, we provide an impulse type of excitation circuit including capacitances 83 which are charged from a suitable source of alternating current 84 through a transformer 85 having a primary winding 86 and secondary windings 87 and 88. Unidirectional conducting devices 89 40 are connected between one terminal of the capacitances 83 and transformer secondary windings 87 and 88 to charge the upper plates of capacitances 83 positive relative to the lower plates. Control electric valves 81 and 82 are rendered conductive at the proper time by means of a transformer 90 having a primary winding 91 and secondary windings 92. The primary winding 91 of transformer 90 in excitation circuit 79 is connected in series relation with the 45 secondary winding of transformer 78 and the secondary winding of transformer 61, so that the potential impressed on the primary winding 91 is the resultant of the potential introduced in this circuit by means of transformer 78 and transformer 61.

The operation of the embodiment of our invention shown in Fig. 3 is substantially the same as that described above in connection with the arrangement shown in Fig. 2, differing only in the 50 manner in which the impulse excitation circuits 79 and 80 of Fig. 3 effects energization of the immersion-ignitor control members 50 of electric valves 44-47. Let it be assumed that the electric valve voltage regulating system is operating 55 so that a voltage is being impressed on the al-

ternating current load circuit 36 through electric valves 46 and 47, switch 43 and terminal 38 of extension winding 35'. When the voltage of circuit 36 decreases below a predetermined minimum value, the voltage responsive device 65 will be moved to the position shown in Fig. 3, introducing in excitation circuit 79 through transformer 61 a potential tending to render control electric valves 81 and 82 conductive. When the instantaneous value of the current through electric valves 46 and 47 is substantially zero, the potential introduced in excitation circuit 79 will be effective to render control electric valves 81 and 82 conductive, thereby permitting the capacitances 83 to discharge through the immersion-ignitor control members 50 of electric valves 45 in the proper predetermined order. In this manner, the time at which the control electric valves 81 and 82 are rendered conductive will be delayed until the instantaneous value of the current through electric valves 46 and 47 is zero. The phase shifting circuits 68 and 69 by the proper adjustment for the most lagging power factor condition of the load imposed on load circuit 36, will impress potentials in substantial phase opposition to the potentials introduced in excitation circuits 79 and 80 by the transformers 61 and 62, so that both groups of electric valves will not conduct at the same time.

While we have shown and described our invention as applied to a particular system of connections and as embodying various devices diagrammatically shown, it will be obvious to those skilled in the art that changes and modifications may be made without departing from our invention, and we, therefore, aim in the appended claims to cover all such changes and modifications as fall within the true spirit and scope of our invention.

What we claim as new and desire to secure 40 by Letters Patent of the United States, is:

1. In combination, a supply circuit, a load circuit, electric translating apparatus interposed between said circuits comprising a plurality of electric valve means for controlling the relative voltages of said circuits, control means responsive to an electrical condition of one of said circuits to effect transfer of the load current among said electric valve means, and means associated with each of said electric valve means for maintaining said control means ineffective until the instantaneous value of said load current is substantially zero.

2. In combination, a supply circuit, a load circuit, electric translating apparatus interposed between said circuits comprising a plurality of electric valve means for controlling the relative voltages of said circuits, means responsive to the voltage of said load circuit to effect transfer of the load current among said electric valve means, and means associated with each of said electric valve means for maintaining the other of said electric valve means nonconducting while one of said electric valve means is conducting.

3. In combination, an alternating current supply circuit, an alternating current load circuit, means interposed between said circuits comprising a transformer winding having a plurality of electrically spaced terminals, electric valve means associated with each of said terminals for controlling the relative voltages of said circuits, a plurality of excitation circuits each associated with a different one of said electric valve means for controlling said electric valve means,

and current responsive means for controlling said excitation circuits to maintain the other of said electric valve means non-conducting when one of said electric valve means is conducting.

3. 4. In combination, an alternating current supply circuit, an alternating current load circuit, means interposed between said circuits comprising a transformer winding having a plurality of electrically spaced terminals, electric valve means 10 means associated with each of said terminals for controlling the relative voltages of said circuits, a plurality of excitation circuits each associated with a different one of said electric valve means for controlling the conductivity of the associated 15 electric valve means, and a plurality of current responsive means each associated with a different one of said electric valve means for controlling said excitation circuits to maintain the other of said electric valve means non-conducting when 20 one of said electric valve means is conducting.

5. In combination, an alternating current supply circuit, an alternating current load circuit, means interposed between said circuits comprising a transformer winding having a plurality of 25 electrically spaced terminals, a pair of electric valve means associated with each of said terminals for controlling the relative voltages of said circuits, said pairs of electric valve means being reversely connected in parallel, a plurality of 30 excitation circuits each associated with a different pair of said electric valve means for controlling the conductivity of said associated electric valve means, and means connected in series relation with each of said pairs of electric valve 35 means for maintaining the other pairs of said electric valve means non-conducting when one pair of said electric valve means is conducting.

6. In combination, an alternating current supply circuit, an alternating current load circuit, 40 means interposed between said circuits comprising a transformer winding having a plurality of electrically spaced terminals, electric valve means associated with each of said terminals for controlling the relative voltages of said circuits, a plurality of excitation circuits each associated 45 with a different one of said electric valve means for controlling the conductivity of said associated electric valve means, means responsive to an electrical condition of one of said first mentioned 50 circuits for controlling said excitation circuits to effect transfer of the load current between said electric valve means, and restraining means associated with each of said electric valve means for controlling the excitation circuits associated 55 with the other of said electric valve means to effect said transfer only when the instantaneous value of the load current is substantially zero.

7. In combination, a supply circuit, a load circuit, electric translating apparatus interposed between 60 said circuits comprising a plurality of electric valve means for controlling the relative voltages of said circuits, each of said electric valve means including a pair of arc discharge paths of the type employing immersion-ignitor control 65 members and being reversely connected in parallel, means responsive to an electrical condition of one of said circuits to effect transfer of the load current among said electric valve means, a plurality of excitation circuits each associated 70 with a different one of said electric valve means

for energizing said control members, and means associated with each of said electric valve means for controlling said excitation circuits to maintain the other of said electric valve means non-conducting when one of said electric valve means 5 is conducting.

8. In combination, a supply circuit, a load circuit, electric translating apparatus interposed between said circuits comprising a plurality of electric valve means for controlling the relative voltages of said circuits, a plurality of excitation circuits each associated with a different one of said electric valve means for controlling the conductivity of said electric valve means, a plurality of current responsive means each connected in series relation with a different one of said electric valve means for controlling the associated excitation circuits to maintain the other of said electric valve means non-conducting when one of said electric valve means is conducting, and means 10 interposed between said current responsive means and said excitation circuits for controlling said excitation circuits to effect a transfer of the load current among said electric valve means when the instantaneous value of said load current is substantially zero. 15

9. In combination, a supply circuit, a load circuit, electric translating apparatus interposed between said circuits comprising a plurality of electric valve means for controlling the relative voltages of said circuits, a plurality of excitation circuits each associated with a different one of said electric valve means for controlling the conductivity of said electric valve means, control means 20 responsive to an electrical condition of one of said circuits for controlling said excitation circuits to effect transfer of the load current among said electric valve means, and means responsive to the current conducted by each of said electric valve means for introducing potentials in the excitation circuits of the other of said electric valve means to render said control means ineffective until the instantaneous value of said load current is substantially zero. 25

10. In combination, a supply circuit, a load circuit, electric translating apparatus interposed between said circuits comprising a plurality of electric valve means for controlling the relative voltages of said circuits, a plurality of excitation circuits each associated with a different one of said electric valve means for controlling the conductivity of said electric valve means, means responsive to an electrical condition of one of said first mentioned circuits to effect transfer of the load current among said electric valve means, current responsive means connected in series relation with each of said electric valve means for maintaining the other of said electric valve means non-conducting when one of said electric valve means is conducting, and means comprising phase shifting circuits interposed between said current responsive means and said excitation circuits for introducing in said excitation circuits voltages which vary in accordance with the load current to effect said transfer of the load current when the instantaneous value of said load current is substantially zero. 40 45 50 55 60 65
